TOBACCO PRODUCTS AND METHOD OF MAKING

Leo J. Novak, Dayton, Ohio, assignor to The Commonwealth Engineering Company of Ohio, Dayton, Ohio, a corporation of Ohio

Application February 11, 1955, Serial No. 487,699

19 Claims. (Cl. 131—17)

This invention relates to tobacco products and more particularly to products comprising tobacco in comminuted or particulate form and adapted for smoking.

The manufacture of cigars is quite complex. In making even low-price cigars, for example, it is not unusual for some fifteen to twenty different types and grades of tobacco to be blended together, and a large proportion of the work is done by hand, which increases the cost and slows up production. The same problems are met in making cigarettes and pipe tobacco.

An object of this invention is to provide improvements in the blending of tobaccos.

Another object is to provide an improved bonding agent for particles of tobacco and such adjuvants as flavoring agents, combustion catalysts and adsorbents as may be mixed therewith.

A further object is to simplify the making of tobacco products.

Those and other objects of the invention are accomplished by incorporating with the comminuted or particulate tobacco, as binder therefor, carboxymethyl dextran.

In practicing the invention, leaf tobacco that has been treated in the usual way, that is by drying, curing, sweating, fermenting, aging and similar treatments, and then comminuted in any of the usual types of grinders or pulverizers to particles passing through a 20-mesh screen, and a substantial portion of which are of a size to pass through a 40-mesh screen, is thoroughly mixed with a viscous aqueous solution or gel of carboxymethyl dextran to obtain a plastic mass in which, if different grades and/or types of tobaccos are present, these are blended to a homogeneous, uniform product. The plastic mass of tobacco is rolled out into sheets or otherwise pressed or formed into desired shapes, e. g., extruded as a rod or ribbon and the water is evaporated, leaving a coherent tobacco product.

The process is illustrated diagrammatically in the accompanying flowsheet.

The amount of the aqueous solution or gel comprising carboxymethyl dextran mixed with the comminuted tobacco is just sufficient to form a workable plastic mass. Because of the extraordinary water-imbibing and water-thickening power of carboxymethyl dextran, smaller amounts of the dextran ether accomplish this objective than are required for other binders that have been proposed for this use in the prior art. In general, one to three parts by weight of aqueous 3% to 6% carboxymethyl dextran solution or gel to one part of comminuted tobacco yields a mass of the desired consistency and workability. The carboxymethyl dextran may constitute from about 2 to 4.5% of the finished product.

The carboxymethyl dextran facilitates blending of the various types and grades of tobacco and of the tobacco with other adjuvants, to result in a uniform, homogeneous product having essentially the smoking quality of the starting leaf tobacco and which burns easily. The taste and aroma of the tobacco are not impaired by the sub-

2

stantially tasteless and odorless carboxymethyl dextran.

Carboxymethyl dextran may be prepared as described in the pending application of Leo J. Novak et al., Serial No. 346,016, filed March 31, 1953. Briefly, the selected dextran and a carboxymethylating agent are reacted together in an aqueous alkaline medium, the carboxymethyl groups being substituted for one or more hydroxyl groups in the dextran molecule. Suitable carboxymethylating agents are chloracetic acid, sodium chloracetate or chloracetamide. The reaction may be carried out in an aqueous solution of a strong alkali metal hydroxide such as sodium, potassium or lithium hydroxide. The ether may be obtained by reacting the dextran in aqueous solution or suspension with an excess of sodium or potassium hydroxide at a temperature of 50° C. to 100° C. for a time ranging from about ten minutes to two hours. The molar ratio of sodium or potassium chloracetate to dextran may be between 2:1 and 12:1, the molar ratio of sodium or potassium hydroxide between 5:1 and 15:1, and the molar ratio of water to dextran between 70:1 and 120:1. The resulting ethers have a D. S. (degree of substitution or average number of carboxymethyl groups per anhydroglucopyranosidic unit) of less than 1:0 up to 3:0, say 0.5 to 3.0.

The reaction product is a viscous mass comprising the sodium or potassium salt of the ether, which may be precipitated by adding any water-miscible alcohol or ketone, such as methyl, ethyl, propyl, isopropyl or t. butyl alcohol, or acetone, to the crude reaction mass.

The free ether may be recovered by mixing the salt with water, acidifying to pH about 2.0—3.0, and precipitating the ether by means of a water-miscible alcohol or ketone. The pH of 2.0—3.0 is not critical and the precipitation can be effected at other pH values.

The dextran may be synthesized from sucrose by appropriate microorganisms such as those of the *Leuconostoc mesenteroides* or *L. dextranicum* types, or their enzymes, and may be the native gum separated from the fermentate and having a very high molecular weight, or a lower molecular weight dextran resulting from hydrolysis of the native product. In general, the molecular weight of the dextran may be between 2000 and that of the native product.

The carboxymethyl ether may contain from 0.5 to 3.0 carboxymethyl groups per A. G. U. aqueous solutions or gels of the carboxymethyl ether derived from microbiologically produced, high molecular weight water-soluble native dextran such as native *L. m.* B-512 dextran, and containing an average of about 1.0 carboxymethyl group per A. G. U. may be preferred because of the capacity of those ethers to imbibe substantial amounts of water and to undergo pronounced swelling and hydration without a true colloidal aqueous solution of the ether being formed. The plastic mass comprising the carboxymethyl dextran and water has a substantially dry appearance and feel.

Viscous aqueous solutions or gels of the alkali metal salt formed as intermediate in the production of the carboxymethyl dextran may be used, also, with satisfactory results.

The highly viscous aqueous solutions or gels of the carboxymethyl dextrans or salts permit the finely divided tobacco to be worked into a cohesive pliable mass that can be sheeted or rolled without difficulty and on removal of the water the dextran ether or salt remains as a film on the particles to bind them into a cohesive mass which does not crumble readily.

The dextran ether and its salt have advantages over cellulose derivatives for the present purposes. One advantage is the relative ease of purifying the starting dextran and of obtaining the derivatives in pure form for optimum smoking compatibility of the ether or salt

with the tobacco. Another advantage is that combustion of dextran does not give rise to the carcinogenic hydrocarbon benzpyrene which has been found to be a combustion product of cellulose. A further advantage is that the carboxymethyl dextrans produce aqueous solutions or gels of a given thickness or viscosity in smaller concentrations than any of the available carboxymethyl celluloses or other water-soluble cellulose derivatives. For example, the carboxymethyl ether of native *L. m. B*-512 dextran having an average D. S. of about 1.0 thickens water to an extent that is only attained with commercially available carboxymethyl celluloses when from 3 to 4 times the amount of the cellulose ethers are used.

It is conventional to include 1% to 2% by weight of bentonite or like mineral in tobacco products for the purpose of improving the coherency of the final product. The bentonite is not required for the purpose when carboxymethyl dextran binder is used, although it may be desirable to include it for assisting in absorbing and filtering out tarry constituents and alkaloids of the tobacco smoke drawn through the unsmoked portion of the cigar or cigarette.

Harmless plasticizers such as glycerine may be included for increasing the flexibility of the sheeted product, although the need for plasticizers is decreased when the dextran ether or its salt is used.

The following examples are illustrative of specific embodiments of the invention, it being understood that these examples are not intended as limitative.

Example I

A mixture of water and 0.5% by weight of carboxymethyl dextran derived from *L. m. B*-512 native dextran and having a D. S. of about 1.1 is prepared and mixed with a blend of 40 parts Wisconsin binder tobacco, 44 parts of Pennsylvania tobacco and 16 parts of Havana tobacco comminuted to a particle size of 20 to 40 mesh. The resulting plastic mass is extruded through a slit 2 inches long and $\frac{1}{40}$ inch wide. This extruded ribbon of tobacco paste is deposited on a moving band of wire cloth and dried on the band by means of air at 50° C. The drying is continued until the ribbon has a moisture content of 19%-20%, after which it is cut into shreds of the size for cigarettes. The cigarette is made in the usual way.

Example II

Air-dried Pennsylvania leaf tobacco comminuted to a particle size of 20 to 40 mesh is thoroughly mixed with a mixture of water and 0.1% by weight of the sodium salt of the carboxymethyl ether of Example I. The pasty, plastic but relatively dry-appearing mass is placed on plate glass and covered with a sheet of wax paper. The sheet is pressed out by rolling between the wax paper and plate glass into a layer about $\frac{1}{60}$ inch thick. The wax paper is removed and the plastic layer on the glass is transferred to a drying chamber and dried by circulating air heated to 50° C. The drying is continued until the product has a moisture content of about 16%, after which it is taken from the drier, put up in the form of a cigar and provided with a thin wrapper of Sumatra tobacco.

Carboxymethyl ethers of other native and hydrolyzed dextrans and having a D. S. of 0.5 to 3.0, are also effective as binders for the tobacco particles, as are their alkali metal salts.

Additives which are commonly used to impart various properties to the tobacco products may be mixed with the comminuted tobacco or with the plastic mass comprising the latter and the carboxymethyl dextran. Such additives include flavoring agents and substances which have a favorable effect on the texture and porosity of the product such as diatomaceous earth. Use of the carboxymethyl dextran as binder and blending agent for

the tobaccos results in a homogeneous product which can be readily reproduced, has the same burning characteristics and taste at all portions of the product, and which is economical in that, the tobacco particles being bonded, the coherent products are easy to shape and handle.

Since it is apparent that various changes and modifications may be made in practicing the invention without departing from the spirit and scope thereof, it will be understood that it is not intended to limit the invention except as defined in the appended claims.

What is claimed is:

1. A tobacco product adapted to be smoked and comprising tobacco particles bonded together by a substance selected from the group consisting of carboxymethyl dextran containing an average of 0.5 to 3.0 carboxymethyl groups per anhydroglucose unit and alkali metal salts thereof.
2. A tobacco product adapted to be smoked comprising tobacco particles bonded together by carboxymethyl dextran containing an average of 0.5 to 3.0 carboxymethyl groups per anhydroglucose unit.
3. A tobacco product adapted to be smoked comprising tobacco particles bonded together by the sodium salt of carboxymethyl dextran containing an average of 0.5 to 3.0 carboxymethyl groups per anhydroglucose unit.
4. A substantially homogeneous tobacco product adapted to be smoked comprising a blend of different tobaccos in particulate form, the particles being bonded together by a substance selected from the group consisting of carboxymethyl dextran containing an average of 0.5 to 3.0 carboxymethyl groups per anhydroglucose unit, and alkali metal salts thereof.
5. A tobacco product according to claim 4, characterized in that the blended tobaccos are of different types.
6. A tobacco product according to claim 4, characterized in that the blended tobaccos are of different grades.
7. A tobacco product according to claim 4, characterized in that the blended tobaccos are of different types and grades.
8. A cigar comprising particles of tobacco bonded together by carboxymethyl dextran containing an average of 0.5 to 3.0 carboxymethyl groups per anhydroglucose unit.
9. A cigarette comprising particles of tobacco bonded together by carboxymethyl dextran containing an average of 0.5 to 3.0 carboxymethyl groups per anhydroglucose unit.
10. A tobacco product adapted to be smoked comprising particles of tobacco bonded together by a carboxymethyl ether of native, high molecular weight, microbiologically produced water-soluble dextran containing an average of about 1.0 carboxymethyl group per anhydroglucopyranosidic unit.
11. The method of making tobacco products adapted to be smoked which comprises mixing particulate tobacco with a viscous to gel-like mixture of water and a substance selected from the group consisting of carboxymethyl dextran containing an average of 0.5 to 3.0 carboxymethyl groups per anhydroglucose unit and alkali metal salts thereof to obtain a plastic mass, forming the mass into the desired shape for smoking, and drying the shaped product to obtain a shaped tobacco product in which the tobacco particles are bonded together by the carboxymethyl dextran or salt.
12. The method according to claim 11, in which particles of different tobaccos are blended into a substantially homogeneous mass by mixing with the mixture of water and carboxymethyl dextran or salt.
13. The method according to claim 12, in which the tobaccos blended to a substantially homogeneous mass are of different types.
14. The method according to claim 12, in which the tobaccos blended to a substantially homogeneous mass are of different grades.
15. The method according to claim 12, in which the

tobaccos blended to a substantially homogeneous mass are of different types and grades.

16. The method of making an improved cigar which comprises mixing particulate tobacco with a viscous to gel-like mixture of water and a substance selected from the group consisting of carboxymethyl dextran containing an average of 0.5 to 3.0 carboxymethyl groups per anhydroglucose unit and alkali metal salts thereof to obtain a plastic mass, sheeting the mass, rolling the sheet to obtain a cigar, and drying the rolled product to obtain a cigar in which the particles are bonded together by the carboxymethyl dextran or salt.

17. The method according to claim 16, characterized in that different tobaccos are mixed with the mixture of water and carboxymethyl dextran or salt and blended into a homogeneous plastic mass as a result of the mixing.

18. The method of making an improved cigarette which comprises mixing particulate tobacco with a viscous to gel-like mixture of water and a substance selected from the group consisting of carboxymethyl dextran containing an average of 0.5 to 3.0 carboxymethyl groups per anhydroglucose unit and alkali metal salts thereof to ob-

tain a plastic mass, extruding the mass in the shape of ribbon, drying the ribbon, shredding the ribbon and forming the shreds into a cigarette in which the tobacco particles are bonded together by the carboxymethyl dextran or salt.

19. The method according to claim 18, characterized in that different tobaccos are mixed with the mixture of water and carboxymethyl dextran or salt and blended into a homogeneous plastic mass as a result of the mixing.
